Primary Examiner — Clare E Heflin(74) *Attorney, Agent, or Firm* — McCarter & English, LLP(57) **CLAIM**

What is claimed is an ornamental design for a door light, as shown and described.

DESCRIPTION

FIG. 1 is a perspective view of a door light showing the front and the left side;

FIG. 2 is a front elevational view of the door light of FIG. 1;

FIG. 3 is a rear elevational view of the door light of FIG. 1; FIG. 4 is a right side elevational view of the door light of FIG. 1;

FIG. 5 is a left side elevational view of the door light of FIG. 1;

FIG. 6 is a top plan view of the door light of FIG. 1; and, FIG. 7 is a bottom plan view of the door light of FIG. 1. In the drawings, the broken (phantom) lines depict unclaimed subject matter only and form no part of the claimed design.
